UNITED STATES PATENT OFFICE.

GILBERT A. COLBY, OF CHICAGO, ILLINOIS.

STEAM-BOILER.

SPECIFICATION forming part of Letters Patent No. 436,033, dated September 9, 1890.

Application filed October 22, 1888. Serial No. 288,837. (No model.)

To all whom it may concern:

Be it known that I, GILBERT A. COLBY, of Chicago, in the county of Cook and State of Illinois, have invented certain new and useful Improvements in Steam-Boilers; and I do hereby declare that the following is a full, clear, and exact description thereof, reference being had to the accompanying drawings, and to the letters of reference marked thereon, which form a part of this specification.

This invention relates to that class of steam-generators known as "water-tube boilers," or those boilers in which the water is held in a plurality of tubes which are exposed to the action of the fire.

The invention consists in the matters hereinafter described, and pointed out in the appended claims.

In the accompanying drawings illustrating my invention, Figure 1 is a vertical longitudinal section of a boiler constructed in accordance with the invention. Fig. 2 is a front elevation of the same, with part of the boiler-casing broken away to show the water-head. Fig. 3 is a view in elevation of the rear end of the boiler, a portion of the water-head being broken away to show the same in sectional view. Fig. 4 is an enlarged detail section, showing one of the hand-hole plates for closing the hand-holes in the water-head and the devices for securing the same in place. Fig. 5 is a detail view of one of the said hand-hole plates. Fig. 6 shows the cap-plates employed for holding the hand-hole plates in place. Fig. 7 is an enlarged detail in section, showing the packing-rings placed between the water-heads at the point of communication.

As illustrated in said drawings, A A A are vertical water-heads located side by side in contact with each other at the front end of the boiler, and A' A' A' are similarly arranged water-heads at the rear end of the boiler.

B B B indicate a series of water-tubes arranged in an inclined position and extending between the said water-heads A A A and A' A', with which said tubes B B B are connected at their ends. The tubes B B B are located at the lower part of the boiler adjacent to the furnace so that the water therein is exposed to the most intense heat from furnace-fire.

Above the tubes B B B is located a second

set or series of water-return tubes C C C, which are arranged horizontally, and are also connected at their ends with the water-heads A A A and A' A' A'. Said tubes B B B and C C C, together with the said water-heads A A A and A' A' A', form a closed circuit, in which the water is adapted to freely circulate, the water in the inclined tubes B B rising as it is heated and flowing upwardly to the water-heads A A A, and then passing through the return-tubes C C backwardly to water-heads A' A' A'. The water-heads A' A' A' terminate a short distance above the level of the return-tubes C C; but the heads A A A are extended a considerable distance above said pipes.

D D D are a third set or series of pipes located above the return-tubes C C C and connected at their front ends with the upper parts of the water-heads A A A, which extend above return-tubes. At the rear end of the boiler said pipes D D D are connected with a horizontal steam chamber or header E, herein shown as arranged immediately over the several water-heads A' A' A'. Said pipes D D D are exposed to products of combustion from the furnace, and act as superheating-pipes to dry the steam. Said pipes also afford space for the storage of steam.

The water-line of the boiler will commonly be located about on a line with the centers of the uppermost of the return-tubes C C C, thereby leaving steam-spaces in the upper parts of said tubes, which spaces afford communication between the small steam-spaces at the top of the rear water-heads A' A' A' and the upper parts of the front water-heads A A A, and thus allow the steam generated in the return-tubes and rear water-heads to flow freely into the steam-chambers formed by the said upper parts of said front water-heads, from which chambers the steam passes into the steam-heating tubes D D D. Steam is taken from the boiler by means of an exit-pipe E', Fig. 3, connected with the header E near one end thereof. A safety-valve, when employed, may be conveniently located upon said header E, as indicated at E'.

In water-tube boilers of the class herein shown, embracing a water-head from the upper part of which steam is taken, it has been found that when the said water-head is made

of sufficient width only to afford suitable circulation of the water the area of the head at the water-level is too small for the free separation of the steam from the water, and thereby renders liable the carrying up of particles of water with the steam-heating tubes. In other words, the surface of the water in such water-heads is insufficient to allow the proper separation of the steam from the water, the rapid rising of the steam globules through the water having the effect of carrying the water particles a considerable distance above the normal water-level, thereby allowing said particles to be drawn or carried into the heating-tubes with the steam. The objections are obviated in the boiler herein shown by providing the water-heads A at the level of the water with separating-chambers A² A² A², formed by making the said water-heads of considerably greater width at or adjacent to the surface of the water. This construction gives a relatively-large area of water-surface for the separating of steam from the water, while at the same time avoiding the employment of a water-head, which is unnecessarily large and bulky in its parts above and below the water-line. In other words, my construction in this particular embraces the making of a narrow water-head of sufficient size only for the proper circulation of the water except at the water-level, where the water-head is horizontally enlarged or made of much greater width than heretofore, forming a separating space or chamber, located only at the point where an extended water-surface is needed—namely, at the water-line.

As a convenient and preferable construction, the enlarged or widened parts of the water-heads, which constitute the steam-separating chambers, are made of sufficient height to receive the ends of the several water-return tubes C C C, as clearly shown in the drawings. When this construction is used, it is entirely obvious that the water which rises or moves upwardly within the front water-head, owing to the upward movement of steam therein, flows backwardly within the separating-chambers A² toward the return-tubes, so that the water flows rearwardly and into the said tubes while the steam separates therefrom and passes upwardly into the steam-heating tubes D D D. It is to be understood, however, that the separating-chambers formed by enlargement of the water-head at the water-level may be of other shape than the particular one shown, and that it is only strictly necessary, as far as the separation of the steam from the water is concerned, that the uppermost row of return-pipes should be connected with the said separating-chamber.

The several front water-heads A A A are provided with vertical partitions a a a, extending from the bottom to the top thereof and arranged at such distance apart as to include between them the ends of one vertical row of the several sets of tubes B, C, and D.

Said tubes are desirably arranged in horizontal rows and with the tubes of one row over the spaces between the tubes of the adjacent row beneath it, the tubes being arranged as closely together as possible for the proper distribution of the heat. The said partitions a a a are therefore shaped in the form of a series of opposite bends or curves to pass between the ends of the pipes. The said partitions at points within the separating-chambers A² A² A² are connected by stays a² a². The rear water-heads A' A' A' are provided with similar partitions a' a'. The purpose of the partitions a a a a' a' is to confine the steam passing from each vertical row of water-tubes and to carry the same to the steam-heating tubes, which are immediately above the same. The object of thus confining the steam is to prevent an unequal flow of steam in the different parts of the boiler—such as would be liable to occur in case such partitions were absent—by the natural tendency of all the steam in the boiler to pass through the steam-heating tubes nearest the steam-exit pipe of the boiler. The passage of large proportion of steam therein through the steam-tubes nearest the exit will obviously not only tend to deprive the other tubes of the supply of steam which should be subjected to heat therein, but tends by the rapidity of its movement to lift the water and carry it out through the exit-pipe. The rapid passage of steam through said pipes which are nearest the exit-passage in the manner described, furthermore, obviously prevents a sufficient heating of such steam to vaporize the water carried through said tubes with or by the steam. In a boiler in which the exit-pipe is located at one end of the header E—in the manner herein shown, for instance—in the absence of the partitions a a' most of the steam will pass through the heating-pipes which enter the header near the exit-pipe, with the disadvantages hereinbefore mentioned. By employing the said partitions a a', therefore, an equal flow of steam through all of the heating-pipes D D is obtained, while at the same time the steam-heating capacity of the generator is in no way limited.

The water-heads A A', provided with partitions arranged in the manner described, may be constructed in practice in any manner found convenient or desirable. As herein shown, however, the water-heads are made of cast metal, and the partitions are made integral with the walls of the heads.

I have herein shown the several water-heads at each end of the boiler as arranged in contact with each other, and as having their adjacent side walls which are in contact curved to correspond in shape with the partitions a a', so that the several tubes B, C, and D, which are connected with the several water-heads, need be placed at no materially greater distance apart along the line at which the water-heads are joined than elsewhere. This construction is of course employed in order to

save space and to enable all of the tubes in a single boiler to be disposed at practically equal distances apart. I do not, however, wish to be limited to this particular construction in the water-heads. Nor do I wish to be limited to the employment of any particular number of water-heads, it being entirely obvious that the same advantages arising from the use of the vertical partitions and other features of novelty herein shown may be obtained when one or more than one of such water-heads is used at each end of the boiler. In case a plurality of water-heads is present at each end of the boiler, as in the boiler illustrated, this construction is employed for convenience in making the water-heads when the latter are of cast metal.

The several water-heads A A A at the front of the boiler are connected with each other by means of horizontal bolts $a^4 a^4$, which engage lugs cast upon the said water-heads at the upper and lower part thereof in a manner illustrated. The rear water-heads A' A' A' are desirably arranged to communicate with each other at their lower parts by means of openings $a^5 a^5$ in the adjacent side walls of the heads. Packing-rings X are placed around said openings between the said adjacent walls of the heads, so as to form close joints to prevent the escape of water at these points. Said rear water-heads are conveniently connected at their upper ends by bolts a^6 passing through lugs cast upon the heads in the same manner as hereinbefore described. In order, however, to insure tight joints about the openings $a^5 a^5$ at the lower parts of the header, a strong or heavy rod A³ is desirably inserted through lugs $a^7 a^7$ on the headers, said rods being provided with a head at one end and with a nut at its other end by which the lower parts of the several headers may be forcibly clamped to each other for the purpose stated. Separate heavy bolts may of course be substituted for the rod A³ in practice. G is a feed-pipe, which extends horizontally across the rear end of the boiler adjacent to the water-heads A' A' A', and is provided with branches g g g, connecting said pipe with each of the said several water-heads. Said feed-pipe G is desirably located at a point opposite the space between the ends of the water-pipes B B and return-pipes C C.

In order to facilitate the prompt and equal distribution of water through the several vertical chambers formed by the partitions $a' a'$, openings A⁴ A⁴ are formed in said partitions and are arranged on or about the same level as the water-pipe. The openings $a^5 a^5$ connect the several water-heads for the purpose of equalizing the quantity of water in the heads, and the passages A⁵ A⁵ at the lower end of the said partitions $a' a'$ serve also to equalize the quantity of water in the spaces between the partitions, and further enable sediment or mud to be taken from the entire lower part of each water-head from a single

hand-hole therein, such hand-hole for the removal of mud being shown at $a^8 a^8$, Fig. 3.

The header E, in the particular construction thereof herein illustrated, is formed by an integral casting, rectangular in cross-section, its inner vertical wall being apertured to receive the ends of the heating-pipes D D. Said header is provided with a series of transversely-arranged partial partitions e e e, located between the ends of the several steam-heating pipes. Said transverse partitions are perforated and serve as stays to hold together the opposite side walls of the header. A partial partition e', somewhat higher than the other partitions e e and extending to a point above the ends of the uppermost row of steam-pipes, is located at the end of the steam-header nearest the steam-exit pipe and between the ends of the said several steam-pipes and said exit-pipe. The end of the steam-header with which the said pipe is connected is bent or curved downwardly and terminates in a downwardly-extending pipe E³, the lower end of which is arranged to communicate with one of the rear water-heads A'. The upper wall of the said steam-header is extended in a downwardly-curved direction past the steam-exit pipe, which latter is arranged in the side wall of the steam-header. As a result of this construction, steam passing between the upper end of the partition e' and the top wall of the header is caused to flow along the said curved wall e² of the header, carrying with it any particles of water therein, which latter are thereby thrown or fall into the pipe E³ and are returned to the water-head, the dry steam passing out through the exit-pipe E'.

e³ is another partial partition extending from the bottom wall of the steam-header toward the curved wall e² thereof below the exit-pipe E' and above the top of the pipe E³. Said partition e³ serves to prevent any of the water particles being caught by the steam and carried out through the exit-pipe, it being entirely obvious that the water particles which are carried along the curved wall e² will be carried by the impetus of their movement below the said partition e³ and will be prevented by said partition from being lifted up to said exit-pipe by the eddying of the steam as it approaches the exit-pipe, or otherwise.

The front wall of the water-heads A A A and the rear or outer walls of the water-heads A' A' A' are provided with hand-holes $a^9 a^9$, arranged opposite or in alignment with the several water and steam pipes hereinbefore described, said hand-holes being for the purpose of enabling the said tubes to be cleaned or removed for renewal or repairs. As an improved means of closing said holes, I employ the construction illustrated in the drawings, and shown more particularly in Figs. 4, 5, and 6. In said drawings, H is a hand-hole plate, which is arranged inside of the water-head, and is fitted at its margins to the mar-

gins of the hand-hole, the hand-hole and plate commonly being circular in form. The plate is held removably in place by devices constructed as follows: I I' are two parts or castings, each of which is semicircular in form, as viewed from the front of the boiler, and which when placed together form a two-part cup-shaped piece or cap adapted to fit at its margins against the edges of the hand-hole 5 at the outer surface of the water-head. The said castings are provided at their adjacent margins with central semicircular notches i i', which when the castings are placed together 10 form a circular bolt-hole. J is a bolt, which passes through said bolt-hole and engages a central screw-threaded aperture h in the hand-hole plate H, the bolt being provided with a head j at its outer end bearing against the outer surface of the parts I I' of the two-part 15 cap. In securing the hand-hole plates in place, said plates are inserted inside of the water-head. The bolt J is then engaged therewith, the parts I I' of the cap then placed on either side of the bolt in engagement with 20 the edges of the hand-hole, and the bolt then tightened up until the head thereof is brought against the said cap and the hand-hole plate firmly clamped against the wall of the water-head. To prevent the hand-hole plate from 25 turning with relation to the two-part cap when the bolt is tightened, said plate is provided with an outward-projecting lug h', and one of the parts I' of the cap is provided with a similar inwardly-extending lug i', said lugs h' i' 30 being of such length that when the parts are placed together the ends of the lugs will extend past each other, as clearly shown in Fig. 4. Said lugs will obviously come in contact with each other in case the plate turns around 35 in the act of tightening the bolt, and thereby prevent farther turning of the plate after the lugs come together.

The hand-hole plates being made larger in diameter than the hand-holes, it is obviously 40 necessary to provide a hole or holes in each of the headers of sufficient size to enable the said plates to be inserted into the interior of the headers, and where the water heads are provided with vertical partitions in the manner illustrated one of such larger hand-holes 45 must be provided between each of the partitions. For this purpose, as shown in the drawings, the front water-heads A A' are provided with hand-holes a¹⁰ a¹⁰ at their upper 50 ends opposite the ends of the uppermost row of heating-tubes D, said hand-holes a¹⁰ being preferably made the same width in one direction as the hand-holes a⁹, but of sufficient length to enable the circular hand-hole plates 55 belonging to the hand-holes a⁹ a⁹ to be inserted therethrough. The hand-hole plates and the two-part caps for closing the said 60 elongated hand-holes a¹⁰ are constructed in the same manner as those hereinbefore described. It is not of course essential that 65 the larger or elongated hand-holes intended to admit the hand-hole plates belonging to

the other hand-holes should be arranged at the upper ends of the water-heads, but this construction is in some respects the more convenient one and will usually be preferred. 70

In attaching the hand-hole plates they may be inserted through the elongated hand-holes and placed opposite the hand-holes to which they belong in any manner found convenient or desirable. One simple way of accomplishing this end consists in securing a string to the hand-hole plate which is to be inserted and dropping the plate through the enlarged or elongated hole and lowering the same by the 80 string until it comes opposite the hole which it is to cover, when the bolt J may be engaged with it and the parts connected in the manner before described. I have herein shown the lug h' upon the hand-hole plate as being 85 provided with a small aperture h², into which a string may be inserted and tied for the purpose described. In the case of the rear wall-heads A' A', the elongated hand-holes a¹⁰ are shown as arranged opposite the uppermost 90 row of the inclined water-tubes B B'.

The furnace and parts adjacent thereto in the particular construction illustrated are made as follows: L is the furnace; L', the bridge-wall; L², the furnace-grate, and l the 95 furnace-doorway. M M are vertical plates or castings, which support the front water-heads of the boiler, and which are also provided with outwardly-extended parts m m for the attachment of the lower part of the front 100 wall K in the manner clearly shown in the drawings, Figs. 1 and 2. l' is the furnace-door, which is hinged at its bottom edge to the said plates M M, and is adapted to swing outwardly and downwardly through the door K' 105 of the wall K when the latter door is open, said furnace-door resting in a downwardly and forwardly inclined position when open, in the manner shown in dotted lines in Fig. 1. The door when in this position prevents the 110 coal from falling into the space between the ash-pit and front wall K during the feeding of the furnace. Said front wall K is desirably provided in its upper part with a hinged door K³, which may be opened for inspection of the 115 front water-heads and for other purposes.

The general arrangement of the furnace-walls may be of any character found desirable or preferable. As herein shown, a vertical partition-wall L³ is arranged to extend 120 upwardly from the bridge-wall L' between and nearly to the top of the inclined water-tubes B. N is a horizontal wall or partition formed by fire-brick or tiles resting upon the uppermost row of pipes C and extending 125 rearwardly from the front water-head about two-thirds of the length of the boiler. Said wall N is connected at its rear end with the upper end of a vertical wall N', which extends downwardly to the top of the inclined 130 water-tubes B. A top wall or cover O for the furnace is conveniently formed by brick or tiles resting upon the top row of steam-heating pipes D, which top row of pipes in the

construction shown are arranged horizontally and suitably supported to sustain the weight of the said top wall by a transverse girder or girders O'. The exit-pipe or smoke-stack P is located near the front of the furnace and opens through the said top wall O into the space between the said top wall and the horizontal partition N.

The several walls and partitions, arranged in the manner described, serve to afford a passage for the flames and products of combustion around or among the several water steam-heating tubes in the manner indicated by the arrows, Fig. 1.

15 I claim as my invention—

1. A steam-generator consisting of opposite water-heads, water-tubes connecting said heads, one of said water-heads being enlarged horizontally at the water-line to form a separating-chamber, and steam-heating tubes connected with the enlarged water-head.

2. A steam-chamber comprising a water-head extending above the water-level of the boiler and having a steam-space formed in its upper part, water-tubes connected with said water-head, and steam-tubes connected with the upper part of said water-head, said water-head being provided with vertical partitions extending from the top of the steam-space of the head to points below the water-level.

3. A steam-generator comprising water-heads located at opposite ends of the generator, inclined water-tubes connected at their ends with said heads, horizontal return-tubes located above the inclined tubes, and also connected with said heads, one of said heads extending above the water-level, forming a steam-space, and steam-heating tubes connected with the steam-space in the head above the water-return tubes, the latter head being provided with vertical partitions extending from the top of the steam-space therein to points below the water-level.

4. A steam-generator comprising water-heads located at opposite ends thereof and extending above the water-level of the same and water-tubes connecting said heads and steam-heating tubes connected with the top of one of said heads, said water-heads being provided with vertical partitions extending from bottom to top of same, which partitions are provided in one of the heads with holes located below the water-level to preserve the same water-level in the spaces between the several partitions, substantially as described.

5. A steam-generator comprising two water-heads, one of which is provided with a steam

space or chamber in its upper part, inclined water-tubes, horizontal water-return tubes, steam-heating tubes connected with said steam space or chamber, and a steam-header connected with said several steam-tubes and provided with a steam-exit, said water-head containing the steam space or chamber being provided with vertical partitions extending from the top of the same to points below the water-level, substantially as described.

6. A steam-generator comprising a plurality of steam-heating tubes and a steam-header connected with said tubes, a water-exit pipe connecting one end of said header with the water-space of the generator, and a steam-exit pipe located at the end of the steam-header adjacent to the said water-exit pipe, said header being provided with a transverse partial partition extending upwardly from its bottom wall between the steam-heating tubes and the steam-exit pipe and having its end wall curved downward toward the said water-exit pipe, substantially as described.

7. A steam-generator comprising a plurality of steam-heating tubes and a steam-header connected with said tubes, a water-exit pipe connecting one end of said header with the water-space of the generator, a steam-exit pipe located at the end of the header adjacent to the water-exit pipe, said header being provided with a transverse partial partition extending upwardly from its bottom wall between the steam-heating tubes and the steam-exit pipe and having its end wall curved downwardly to the said water-exit pipe, and a partial partition e^3 , located in the header over the water-exit pipe, substantially as described.

8. The combination, with a water-head provided with a hand-hole, of a hand-hole cover fitting against the inner face of the water-head and means for holding the same in place, comprising a two-part cup-shaped cap and a bolt engaged with the cap and with the hand-hole cover, substantially as described.

9. The combination, with a water-head provided with a hand-hole, of a hand-hole cover provided with an outwardly-extending lug, a two-part cup-shaped cap provided with an inwardly-extending lug, and a screw-bolt, substantially as described.

In testimony that I claim the foregoing as my invention I affix my signature in presence of two witnesses.

GILBERT A. COLBY.
